UNITED STATES PATENT OFFICE.

ARTHUR PRIDDLE, OF SAN FRANCISCO, CALIFORNIA.

CORNER-PROTECTOR.

1,038,195.

Specification of Letters Patent. Patented Sept. 10, 1912.

Application filed February 9, 1911. Serial No. 607,602.

To all whom it may concern:

Be it known that I, ARTHUR PRIDDLE, a citizen of the United States, residing at San Francisco, in the county of San Francisco 5 and State of California, have invented certain new and useful Improvements in Corner-Protectors; and I do declare the following to be a full, clear, and exact description of the invention, such as will enable others skilled in the art to which it appertains to 10 make and use the same.

This invention relates to improvements in corner protectors.

One object of the invention is to provide 15 a corner protector having an improved construction and arrangement of integral fastening devices whereby the protectors may be readily and firmly secured to the framework without the use of additional fastening devices.

With this and other objects in view, the invention consists of certain novel features of construction, combination and arrangement of parts as will be more fully described 25 and particularly pointed out in the appended claims.

In the accompanying drawings: Figure 1 is a cross sectional view of one form of my protector illustrating the application of the 30 same to a frame work; Fig. 2 is a side view of the blank from which the same is formed; Fig. 3 is a similar view of another form of the invention; Fig. 4 is a cross sectional view of the same; Fig. 5 is a side view of another 35 form of blank showing the invention; Fig. 6 is a detail sectional view of the same on the line 6—6 of Fig. 5; Fig. 7 is a cross sectional view of another form of the invention showing the same applied to a frame work; Fig. 40 8 is a side view of the blank from which the same is formed; Fig. 9 is a view similar to Fig. 7 showing a single form of protector provided with my improved fastening devices; Fig. 10 is a side view of the blank 45 from which the same is formed; Fig. 11 is a cross sectional view of another form of the single protector; Fig. 12 is a side view of the blank from which the same is formed; Fig. 13 is a fragmentary perspective view of 50 one form of the protector showing a modi-

fied construction of the fastening prongs; Fig. 14 is a cross sectional view of the prong on the line 14—14 of Fig. 13; Fig. 15 is a view similar to Fig. 13 showing another form of prong; Fig. 16 is a cross sectional view on the line 16—16 of Fig. 15.

Referring more particularly to Figs. 1 to 6 of the drawings wherein is illustrated one form of the invention, 1 denotes the protector which in these figures is shown as being constructed in double form from a single strip of sheet metal bent lengthwise midway between its ends to form a bead 2. The side members 3 of the protector are bent or curved outwardly toward their inner edges as shown. In the side members 3 near their outer ends are formed anchoring lugs 4 said lugs being preferably struck out of the metal forming the sides as shown, thereby providing means for anchoring the plaster to the corner protector.

The curved inner edges of the side members 3 are adapted to engage the opposite sides of the frame or structure to which the same are to be attached. In the side members of the protector are formed fastening lugs 5 which are also struck from or formed integral with the side members 3. The lugs 5 are tapered to sharp points and are bent outwardly from their inner ends at an angle. 75 The points of the lugs are bent inwardly at a right angle to the main portion of the lugs and form fastening prongs 6 which are adapted to be driven into the frame work and thus firmly secure the protectors in 80 place without the use of additional fastening devices.

The fastening lugs 5 are disposed at suitable intervals along the side members of the protector and said lugs may be arranged in 85 the position shown in Figs. 1 and 2, wherein the lugs are struck out transversely to the side members with their points projecting outwardly or with their points projecting inwardly as shown in Figs. 3 and 4. The 90 lugs may also be arranged longitudinally of the side members of the protector as shown in Figs. 5 and 6.

In Figs. 7 and 8 of the drawing the protector is shown as consisting of side mem- 100

bers or plates 7 arranged at an angle and having short curved outer edges which form oppositely projecting flanges 8 with which is engaged a separate bead 9. The bead 9 when engaged with the flanges serves to hold the outer edges of the plates or sides of the protector together and said bead may be constructed of non-corrosive metal which will not rust and thus stain or show through the plaster. In the side plates 7 near their outer edges are formed anchoring lugs 10 similar to the anchoring lugs 4 of the first form of the invention. The side plates 7 also flare outwardly toward their inner edges which are shaped to fit against the opposite sides of the frame work as shown. On the inner edges of the side plates 7 are formed a series of lugs 11 which may have curved edges or which may be V shaped as shown. At intervals the lugs 11 are bent outwardly as shown at 12 and the points or outer ends of the outwardly bent lugs are bent inwardly at a right angle thus forming fastening prongs 13 which are adapted to be driven into the frame work thus securely fastening this form of the protector in place. The lugs 11 which engage the sides of the frame between the lugs having the prongs serve to brace and hold the protector in position. In practice the lugs 12 of the protector are yielding and are formed in such a manner in respect to one another that the pointed ends thereof will grip the wooden frame work of the structure, whereby the protector may be readily positioned, after which the pointed ends are forced home during the completion of the structure.

In Figs. 9 and 10 is shown a single form of the protector in which only one plate 14 is employed. The plate 14 has formed at suitable intervals along its inner edge a series of V shaped lugs 15 which are alternately bent laterally in opposite directions at suitable angles and have their outer ends or points bent at right angles to form fastening prongs 16 which are driven into the wood and thus securely fasten the protector in place. The inner edge of the metal between the series of lugs 15 is bent laterally in opposite directions and at a suitable angle to engage the opposite sides of the frame, said edges thus forming bracing flanges 17 whereby the protector is centered and held in proper position. In this form the protector is provided with anchoring lugs 18 constructed in the manner described.

In Figs. 11 and 12 is shown another single form of the protector in which the plate 19 has its inner edge cut inwardly at intervals 60 in a zig-zag line to form a series of lugs 20. In thus cutting the metal a series of V shaped points 21 are formed along the opposite edges of the lugs 20. The lugs 20 are alternately bent laterally in opposite direc-

tions and at a suitable angle to engage the 65 opposite sides of the frame work and thus form braces. At intervals certain of the lugs 20 are bent outwardly above the sides 70 of the frame and two or more of the points 21 on the side edges of these lugs are bent inwardly at right angles to form fastening prongs 22 which are adapted to be driven into the wood and thus securely fasten the protectors in place. The last form of the 75 protector is provided with anchoring lugs 23 which are formed as hereinbefore described.

In Figs. 13 and 14 of the drawing is shown a modified form of prong 24 said prong being bent or folded upon itself longitudinally and centrally throughout its entire length, thereby increasing the strength and stiffness of the prong. In Figs. 15 and 16 is shown another form of prong 25 which is provided with a blunt or square end 26 and has its inner portion bent or folded on itself as shown at 27 thereby stiffening the prong. The prong as formed in Figs. 15 and 16 provides shoulders 28 which when driven into the wood or frame structure form a secure 90 hold.

From the foregoing description taken in connection with the accompanying drawings, the construction and operation of the invention will be readily understood without 95 requiring a more extended explanation.

Various changes in the form, proportion and the minor details of construction may be resorted to without departing from the principle or sacrificing any of the advantages of the invention as defined in the appended claims.

Having thus described my invention, what I claim is:

1. A corner protector comprising a plate 105 of metal, a bead formed on the outer edge thereof, a series of anchoring lugs formed therein near its outer edge, bracing flanges formed on its inner edges, fastening lugs struck from the plate, said lugs being bent 110 at an angle at their outer ends to form fastening prongs adapted to be driven into the frame work of the structure to which the protectors are applied.

2. A corner protector comprising a metal 115 plate, a series of fastening devices struck from the plate and bent outwardly and then inwardly at an angle to the outwardly bent portion to form fastening prongs adapted to be driven into the frame work to support 120 the protector in operative position, said prongs having a folded longitudinally disposed portion whereby the same are stiffened.

3. A corner protector comprising a metal 125 plate, a series of fastening devices struck from the plate and bent outwardly and then inwardly at an angle to form fastening

prongs adapted to be driven into the framework to support the protector in operative position, said prongs having a square or blunt end and a folded intermediate portion 5 for increasing the stiffness of the prongs and forming shoulders for providing a firm hold in the object in which the prong is driven.

In testimony whereof I have hereunto set my hand in presence of two subscribing witnesses.

ARTHUR PRIDDLE.
